CIRCUIT BREAKER

Louis M. Brown, Westfield, N. J., assignor to Westinghouse Electric & Manufacturing Company, East Pittsburgh, Pa., a corporation of Pennsylvania

Application July 26, 1940, Serial No. 347,637

11 Claims. (Cl. 200—116)

The invention relates to circuit interrupters of the enclosed type, and more particularly to enclosed circuit breakers which are totally immersed in a body of oil within an enclosing housing or tank.

Circuit breakers for use in hazardous locations where gasoline, naptha, lacquer solvent vapors, and other explosive materials are present, and also where corrosive gases are encountered are usually mounted in an enclosing housing or tank and totally immersed in a body of oil within the housing for complete protection against the above-mentioned conditions. The total immersion of the circuit breaker in oil has heretofore prevented the use of conventional thermally responsive overload trip devices for such breakers because direct contact of the heater element of the thermal unit with the oil destroys the thermal characteristic of the trip device. Moreover, providing a liquid tight casing for the breaker or its trip device is not practical from either an economical or operational standpoint.

An object of the present invention is the provision of a circuit breaker totally immersed in a body of oil within an enclosing housing and embodying a thermally responsive overload trip device, the thermal characteristic of which is unaffected by the oil.

Another object of the invention is the provision of an explosion resisting or corrosion resisting circuit breaker apparatus comprising a circuit breaker having a magnetically responsive and a thermally responsive overload trip device totally immersed in a body of oil within an enclosing housing with means for preventing the thermally responsive unit and its heater from being in contact with the oil.

Another object of the invention is the provision of an improved explosion resisting or corrosion resisting circuit interrupter as previously described which is simple, accurate and reliable in operation, and inexpensive to manufacture.

The novel features that are considered characteristic of the invention are set forth in particular in the appended claims. The invention itself, however, both as to structure and operation together with additional objects and advantages thereof will be best understood from the following detailed description of one embodiment thereof when read in conjunction with the accompanying drawings, in which:

Figure 1 is a vertical sectional view of the circuit breaker housing with the circuit breaker mounted therein.

Fig. 2 is another vertical sectional view of the apparatus taken at right angles to the section of Fig. 1.

Fig. 3 is a fragmentary sectional view on an enlarged scale showing a portion of the circuit

breaker and tank, a part of the tank being broken away to reduce the width of the figure.

Fig. 4 is a perspective view on an enlarged scale of the trip device of the circuit breaker, and

Fig. 5 is an enlarged fragmentary sectional view showing the thermally responsive trip means and a portion of the electromagnetic trip means of one pole of the circuit breaker.

Referring to the drawings, the reference number 9 designates an explosion resisting and corrosion resisting circuit breaker housing which comprises an oil tight metal tank 11 and a cast metal top or cover section 13 which serves to support the tank 11 and close the open end thereof. The tank 11 is removably secured to the cover section 13 by a plurality of captive bolts 15 and cooperating nuts 17, the bolts 15 being carried by brackets 19 secured to the tank 11 in spaced relation around the upper end thereof. The bolts 15 are adapted to extend through openings provided therefor in the lugs 21 which are formed integral with the cover section 13 along the bottom edge, and the nuts 17 are threaded on the upper ends of the bolts 15 to tightly secure the tank to the cover section 13. A gasket 23 is secured to the abutting edge of the cover section 13 to provide a tight seal at the joint between the tank and the cover section.

The rear wall of the cast metal cover section 13 is formed to provide a flat mounting base 25 which projects laterally beyond the sides of the housing, and the base is provided with a plurality of holes 27 for receiving bolts or cap screws to mount the housing on a suitable support. The top and side walls of the cover section 13 are provided with tapped holes 29 for accommodating the incoming and outgoing electrical conductors which lead to the circuit breaker within the housing, it being understood that the electrical conductors are brought into the housing through conduits (not shown), the ends of which are secured in the threaded openings 29.

A multipole circuit breaker indicated generally at 31 is disposed in a vertical position within the lower portion of the housing and is supported from the cover section 13. The circuit breaker is secured by mounting bolts 33 (Figs. 2 and 3) to a vertical mounting plate 35 which is in turn secured by brackets 37 to a pair of spaced vertical supporting bars 39. The supporting bars 39 are carried by the cover section 13, each bar being rigidly secured at its upper end to the cover section 13 by means of a pair of cap screws 41.

The incoming electrical conductors 43 and the outgoing electrical conductors 45 are held clamped in proper position adjacent the upper end of the tank 11 by a pair of transversely ex-

tending clamping bars 47 of insulating material which are secured at their ends by bolts 49 to a pair of brackets 51 carried by the supporting bars 39. The conductors 43 and 45 are also held clamped at a position in back of the circuit breaker 31 by a pair of insulating clamping plates 53 which are secured at their ends to brackets 55 carried by the supporting bars 39. The conductors 43 are electrically connected to the three lower terminal studs 51 of the circuit breaker 31, and the conductors 45 are electrically connected to three spaced terminals 59 carried by the mounting plate 35 below the center of the breaker. The three terminals 59 are in turn electrically connected to the upper terminal studs 61 of the circuit breaker by means of conducting straps 63.

The circuit breaker in the embodiment of the invention shown is of the same general construction as the circuit breaker fully described in Patent 2,047,739 of Harry J. Lingal, issued July 14, 1936, and assigned to the assignee of the present invention.

Referring to Fig. 3, the circuit breaker, briefly, comprises a two part casing 65 of molded insulating material having therein a stationary contact 67 and a cooperating movable contact 69 for each of the three poles. The movable contacts 69 are carried by switch arms 71 which are mechanically connected for simultaneous movement together about a common pivot 73 by means of an insulating tie bar 75. The switch arms are actuated by one overcenter spring mechanism at the center pole of the breaker comprising a pair of toggle links 77 and 79 connected to the center pole switch arm 71 and to a pivoted releasable carrier 81 which is pivoted at 83 on a frame 85 secured to the base of the circuit breaker. A pivoted actuating member 87 is connected by overcenter springs 89 to the knee of the toggle for manually actuating the circuit breaker.

The trip device 91 of the circuit breaker is mounted in the upper end of the circuit breaker casing 65 and normally serves to restrain the pivoted carrier lever 81 in the latched position shown in Fig. 3. The trip device is operable in response to an overload on any of the three circuits controlled by the circuit breaker to effect release of the carrier 81 and thus cause automatic opening of all of the contacts of the breaker. When the breaker is tripped, the actuating member 87 is automatically moved to a tripped indicating position intermediate its "on" and "off" positions. The circuit breaker mechanism is manually reset following tripping by movement of the actuating member 87 to its off position to reset the carrier lever 81 to its latched position in which it is normally held by the trip device 91.

The trip device 91 is a unitary structure entirely assembled upon its own insulating base 93 and is completely removable from the circuit breaker casing 65, the screws 95 and bolts 61 being utilized to mount the trip device in the circuit breaker casing 65 and also to make the necessary electrical connections. The trip device includes a thermally responsive trip element 97 and a magnetically responsive trip means for each of the three poles of the breaker. The three conducting bars or strips 99, one of which is associated with each of the poles of the breaker have the quadruple function of providing terminals for the trip device, of providing energizing means for each of the electromagnetic 75

trip means, of providing heater means for the thermally responsive elements 97, and for providing a mounting means for the entire trip structure.

5 Each thermally responsive trip element 97 is composed of a strip of bimetallic material and is fastened by rivets to one of the conducting strips 99.

As shown particularly in Fig. 5, the conducting strips 99 are bent so as to form two reflex bends 101 and 103. The straight part 105 of the strip 99 is utilized as a single turn conductor for energizing the magnetically responsive trip means, while the loop 101 is utilized as a heater for the thermally responsive trip element 97. The portion of the conducting strip 99 which is used in forming the loop 101 is tapered so as to give a conducting section of gradually increased electrical resistance, thereby forming a heater for the bimetal trip element 97. The straight portion 105 of the strip 99 is not of reduced section and does not heat appreciably while carrying the rated current of the breaker. Each of the conducting strips 99 is fastened by rivets to a frame or bracket 107 which is, in turn, secured to the trip base 93.

The magnetically responsive trip means of each pole comprises a U-shaped core 109 (Fig. 4) of magnetic material secured to the bracket 107, and a movable armature 111 which is movably mounted for movement toward and away from the core 109 by means of a guide pin 113 secured to the armature 111 and slidably mounted in an opening provided therefor in a bracket 115 secured to the frame 107. The armature 111 is biased to unattracted position away from the core 109 by means of a spring 117 interposed between the bracket 115 and a collar on the guide pin 113, as shown in Fig. 5. The straight portion 105 of the conducting strip 99 passes through the U of the stationary core 109 and thus forms a single turn energizing winding for the electromagnetic trip means.

The trip device includes a pivoted latch 119 which is pivoted at 121 (Fig. 3) on a bracket 123 carried on the lower side of the trip base 93, and this latch is biased to latching position in which it engages and restrains the releasable carrier 81 in latching position, as shown in Fig. 3. The latch 119 has an upwardly extending portion which projects through an opening in the trip base 93 and which is adapted to be normally engaged and held by a latch projection 125 carried by a common trip bar 127 to thereby hold the latch 119 in latching position.

60 The common trip bar 127 is of molded insulating material and is adapted to be actuated to effect release of the latch 119, and thereby release of the carrier 81, by any one of the individual trip devices. This trip bar 127 has two downwardly extending arms 129, one at each end, for engaging pivot pins 131 which project through suitable openings in supporting brackets 133 mounted on the trip base 93 at each end. A second projection 135 of the trip bar extends downwardly therefrom and through the agency of a suitable recess engages a compression spring 137 (Fig. 3) which biases the trip bar 127 to latching position.

The heads of the armature guide pins 113 engage in notches provided therefor in the molded trip bar 127, thereby connecting the trip bar to each of the movable armatures 111 for actuation thereby. Three adjusting screws 139 are mounted at the forward edge of the trip bar

each in a position to be engaged by the free end of one of the thermally responsive bimetal trip elements 97, thereby providing for actuation of the trip bar 127 by deflection of any one of the thermally responsive bimetal trip elements 97 when the element is heated a predetermined amount by overload current. A cover 141 of molded insulating material is secured to the upper end of the brackets 133 by fastening screws and this cover cooperates with the base 93 to form an enclosure for the trip device.

Each of the conductor strips 99 is connected at its upper end to one of the upper terminals 61 of the circuit breaker, and is electrically connected at its lower end through the agency of a flexible shunt conductor 142 to the movable contact 69 of its corresponding pole. Thus each electromagnetic trip means is energized by the current flowing through its corresponding pole and each thermally responsive trip element 97 is heated in response to the current flowing through the corresponding pole.

The automatic operation of the circuit breaker is briefly as follows. When an overload current of more than a predetermined magnitude, for example, more than 10 times rated current, occurs in the circuit of any pole of the breaker, the corresponding electromagnetic trip means is energized thereby a sufficient amount to pull its movable armature 111 to attracted position and thereby move the trip bar 127 to effect release of the latch 119 and the releasable carrier 81 of the circuit breaker. The release of the carrier 81 effects automatic opening of the circuit breaker, since the overcenter springs 89 immediately act to rotate the three switch arms 71 to open circuit position, and also effect collapse of the toggle 71 and 79.

When an overload of less than the predetermined magnitude occurs in the circuit of any pole of the breaker, the bimetallic trip element 97 of that pole is heated by the overload current and if the overload persists for a sufficient length of time to heat the bimetallic trip element a predetermined amount, the trip element deflects upwardly away from the circuit breaker mechanism to engage and move the trip bar 127, thereby effecting release of the circuit breaker mechanism and automatic opening of the circuit breaker in the manner previously described.

An operating means is provided for manually operating the circuit breaker 31 from outside of the housing 9. The operating means comprises an operating shaft 143 which projects through a side of the cover section 13 and is rotatably mounted on the cover section in a bearing 145 provided therefor. An operating handle 147 is rigidly secured to the portion of the operating shaft 143 which projects outside of the housing. The operating shaft 143 is provided with a crank arm 149 on the end of the shaft which projects inside of the housing 9, and this crank arm is mechanically connected by a link 151 to a transversely extending operating yoke 153 which is pivotally mounted at 155 on the vertical supporting bars 39. The operating yoke 153 straddles the circuit breaker 31 and is provided with a slot 156 which engages the breaker actuating member 87. The connecting link 151 is pivotally connected at 157 to the free end of the crank arm 149 and its other end is pivotally connected at 159 to one side of the yoke 153.

The operating shaft 143 has a close fit in the opening of its bearing 145 and the length of the

engaged parts of the shaft and bearing is sufficient to make the shaft opening flame proof or flame tight.

5 A body of oil 161 is disposed within the tank 11 to a level above the circuit breaker 31 so that the circuit breaker is completely immersed in the oil and the parts thereof are thereby protected from corrosion. The body of oil also prevents the arcs drawn between the contacts of the breaker upon interruption of the circuit from igniting any explosive gases or materials which may be present in the atmosphere surrounding the apparatus.

15 In order to prevent the oil within the housing from affecting the thermal characteristic of the thermally responsive means of the trip device, a diving bell 163 is provided which is mounted over the upper end of the circuit breaker 31, as shown in Figs. 1 and 2. The diving bell 163 comprises an oil tight metal vessel of generally rectangular form which is closed at the top and sides and open at the bottom. The vessel 163 is secured by bolts 165 to a transverse angle bar 167 which is, in turn, secured at its ends to brackets 169 carried by the vertical supporting bars 39. The lower edge of the vessel 163 is disposed some distance below the trip device 91 of the circuit breaker 31, so that the vessel prevents the oil from rising up around the trip device, by reason of the air which is trapped within the upper portion of the vessel 163, as indicated in Fig. 2. It will thus be seen that the vessel 163 prevents the oil from coming in contact with the thermally responsive trip elements 97 and the heaters 101 of the trip device, thereby preventing the oil from affecting or destroying the thermal operating characteristic of the trip device. Since the trip device is disposed below the level of the oil, the parts thereof are not subjected to the corrosive action of the atmosphere surrounding the apparatus.

25 While the invention has been disclosed in accordance with the provisions of the patent statutes, it is to be understood that various changes in the structural details and form of elements 30 may be made without departing from the essential features of the invention. It is desired, therefore, that the appended claims be given the broadest reasonable construction that is permissible in view of the prior art and the language 35 of the claims.

40 I claim as my invention:

45 1. In combination, a circuit interrupter having relatively movable contacts and thermally responsive means heated in response to the current of the circuit and operable when heated a predetermined amount to cause opening of the contacts, an enclosing housing in which the circuit interrupter is mounted, said housing containing a body of insulating liquid in which the circuit interrupter with its thermally responsive means is totally immersed, and means for preventing the liquid from affecting the thermal operating characteristics of said thermally responsive means.

55 2. In combination, a circuit breaker having relatively movable contacts and thermally responsive means heated in response to the current of the circuit for causing automatic opening of the contacts when said means is heated a predetermined amount, an enclosing housing in which the circuit breaker is mounted, said housing containing a body of insulating liquid in which the circuit breaker with its thermally responsive means is completely submerged, and

means for preventing the liquid from coming in contact with said thermally responsive means.

3. In combination, a circuit breaker having relatively movable contacts and thermally responsive means heated in response to the current of the circuit which is operable when heated a predetermined amount to cause opening of said contacts, an enclosing housing in which the circuit breaker is mounted containing the body of insulating liquid in which the circuit breaker with its thermally responsive means is at least partially submerged, and a vessel closed at the top and sides and open at the bottom surrounding said thermally responsive means to prevent the liquid from coming in contact with the thermally responsive means.

4. In combination, a circuit breaker having relatively movable contacts and a trip unit including a thermally responsive trip element and a heating element therefor heated by the current of the circuit, said thermal trip element being operable when heated a predetermined amount to cause automatic opening of said contacts; an enclosing housing in which the circuit breaker is mounted, said housing containing a body of insulating liquid in which the circuit breaker is at least partly submerged, and a vessel closed at the top and sides and open at the bottom surrounding said trip unit to prevent the liquid from coming in contact with said thermally responsive trip element and said heater element.

5. In combination, a multipole circuit breaker having a plurality of pairs of relatively movable contacts, actuating mechanism for said contacts, and a trip device mounted adjacent the upper end of the breaker having a plurality of thermally responsive trip means one for each of at least two of the poles of the breaker, each trip means being heated in response to the current flowing through its corresponding pole and each being operable when heated a predetermined amount to cause automatic opening of the contacts of the breaker, an enclosing housing in which the circuit breaker is mounted, said housing containing a body of insulating liquid in which the circuit breaker with its trip device is at least partly submerged, and a vessel closed at its top and sides and open at its bottom surrounding the upper end of said breaker and the trip device to prevent the liquid from coming in contact with said thermally responsive trip means.

6. In combination, a circuit breaker having relatively movable contacts, operating means therefor, and a trip device operable in response to predetermined current conditions to cause automatic opening of said contacts, an enclosing housing in which the circuit breaker is mounted, said housing containing a body of insulating liquid in which the circuit breaker with its trip device is at least partly submerged, and a vessel closed at the top and sides and open at the bottom surrounding said trip device, the bottom edge of said vessel extending into said liquid below the surface of the liquid.

7. In combination, a circuit breaker having relatively movable contacts, operating means therefor, and a trip device adjacent the upper end of the breaker operable in response to predetermined overload conditions to cause automatic opening of the contacts, said trip device including electromagnetic trip means energized by the current of the circuit operable to cause instantaneous tripping of the breaker whenever

the current exceeds a predetermined magnitude, and thermally responsive trip means heated in response to the current of the circuit and operable to cause tripping of the breaker when said

thermally responsive means is heated a predetermined amount by overload current, an enclosing housing in which the circuit breaker is mounted, said housing containing a body of insulating liquid in which said breaker and its trip device are at least partly submerged, and a liquid tight hood open at the bottom disposed over the trip device for preventing the liquid from rising in contact with the heating portions of the trip device.

15 8. In combination, a housing comprising a top section and a tank removably secured to said top section, a circuit breaker mounted in said housing and supported from said top section of the housing, said circuit breaker having a trip device adjacent the upper end thereof including a thermally responsive trip means heated in response to the current of the circuit and operable when heated a predetermined amount to cause opening of the breaker, said tank containing a body of insulating liquid in which the circuit breaker with its trip device is completely immersed, and a liquid tight open bottomed vessel supported from said top section and surrounding the upper end of the breaker where the trip device is located for preventing the liquid from coming in contact with the trip device and its thermally responsive trip means.

35 9. In combination, a circuit breaker having relatively movable contacts, and thermally responsive means heated in response to the current of the circuit which is operable when heated a predetermined amount to cause opening of said contacts, an enclosing housing in which the circuit breaker is mounted containing a body of insulating liquid in which the circuit breaker is at least partially submerged, and a vessel completely closed at its top and sides and open at the bottom surrounding said thermally responsive means, the open bottom of said vessel extending into said liquid below the surface thereof.

40 10. In combination, a circuit interrupting device having means operable in response to predetermined abnormal conditions of the circuit to cause said device to interrupt the circuit, an enclosing housing in which said circuit interrupting device is mounted, said housing containing a body of insulating liquid in which said circuit interrupting device is at least partially submerged, and a vessel closed at its top and sides and open at the bottom surrounding at least the predetermined abnormal condition responsive means of the circuit interrupting device, the open bottom of said vessel extending into said liquid below the surface thereof.

45 11. In combination, a circuit interrupter having a thermally responsive means heated in response to the current of the circuit and operable when heated a predetermined amount to cause said interrupter to interrupt the circuit, an enclosing housing in which said circuit interrupter is mounted, said housing containing a body of insulating liquid in which said circuit interrupter and its thermally responsive means is submerged, and a vessel closed at its top and sides and open at the bottom surrounding said thermally responsive means to prevent said liquid from coming in contact with said thermally responsive means.

LOUIS M. BROWN.
